Primary Examiner — Susan Moon Lee**CLAIM**

I claim the ornamental design for a feeding platter for pets, as shown and described.

DESCRIPTION

FIG. 1 is a top view of a feeding platter for pets;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom view thereof; and,

FIG. 7 is an isometric view thereof.

The article in which the design is embodied is intended to be used for attracting and feeding domestic pets such as dogs and cats.

The characteristic feature of the design resides in the shape of the object as defined by its periphery; by the indentations or reliefs in the top surface of the object; and the textured top surface.
